ATTORNEY

UNITED STATES PATENT OFFICE.

ALBERT L. HARVEY, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL SYSTEM.

Application filed January 25, 1919. Serial No. 273,037.

To all whom it may concern:

Be it known that I, ALBERT L. HARVEY, a citizen of the United States, and a resident of Wilkinsburg, in the county of Allegheny and State of Pennsylvania, have invented a new and useful Improvement in Control Systems, of which the following is a specification.

My invention relates to motor-control systems.

The object of my invention is to provide an improved motor-control system which shall be especially useful at times when the voltage of the source of power for the motor falls below a predetermined value.

My invention finds particular application in connection with motors, such as fan and pump motors, which are employed in places that are not easily accessible, such as mines, where frequent visits are inconvenient and the constant presence of an attendant is undesirable. According to my invention, upon the failure of voltage, instead of the motor becoming disconnected from the line, the accelerating resistor is automatically reinserted into circuit. Upon the return of power to the line, the motor is automatically restarted, with the accelerating resistor in series therewith, so as to protect the motor windings from injury. A relay is provided for protecting the motor from the effects of overload conditions.

The single figure of the accompanying drawing is a diagrammatic view of circuits and apparatus illustrating my invention.

A motor having an armature 1 and a shunt field-magnet winding 2, is connected between line conductors 3 and 4. Although I have illustrated a shunt motor, a compound motor or a series motor may be employed, if desired. An accelerating resistor 5 is connected in series with the armature 1 and a resistor may be provided in the circuit of the shunt field-magnet winding 2. A contactor 7, having an energizing coil 8, the circuit of which may be closed by a push-button 9, is adapted to close the circuits of the armature 1 and the field-magnet winding 2. A plurality of contactors 10, 11, 12 and 13 are provided for short-circuiting the resistor 5, the contactors having actuating coils 14, 15, 16 and 17, which are respectively controlled by current-limit relays 18, 19, 20 and 21, that are respectively mechanically

connected to the contactors 7, 10, 11 and 12. 55 An overload relay 24 is provided, having an actuating winding 25 in series with the armature 1 for opening the circuit of the coil 8 when the current traversing the armature 1 exceeds a predetermined value. 60

A low-voltage relay 26, having an actuating coil 27 in series with an adjustable resistor 28, controls the circuit of the coil 14 of the contactor 10.

The operation is as follows: When the 65 push-button 9 is depressed, a circuit is established which extends from the line conductor 3, through the coil 25, the overload relay 24, the coil 8 and the push-button 9, to the line conductor 4. The contactor 7 is 70 thereupon closed to establish the armature circuit which extends from the line conductor 3, through the coil 25, contactor 7, the energizing coil of the current-limit relay 18, the resistor 5, and the armature 1 75 to the line conductor 4. A circuit is also established for the shunt field-magnet winding 2 from the contactor 7, by way of a conductor 22, through the shunt field-magnet winding 2 to the line conductor 4. The 80 motor is thereupon started at slow speed. A circuit is established also from the line conductor 3, through the coil 25, the overload relay 24, the coil 27, the resistor 28 and the push-button 9, to the line conductor 4. This 85 will effect the closing of the low-voltage relay 26.

The closing of the contactor 7 releases the current-limit relay 18, which will remain open so long as the current traversing the 90 armature circuit exceeds a predetermined value. Upon the closing of the relay 18, a circuit will be established from the line conductor 3, through the coil 25, the overload relay 24, the current-limit relay 18, the actuating coil 14, the low-voltage relay 26 and the push-button 9, to the line conductor 4. The contactor 10 will thereupon be closed, whereupon the motor-circuit will extend from the line conductor 3 through the coil 100 25, the contactor 7, the coil of the relay 18, by way of a conductor 23, the contactor 10, the coil of the current-limit relay 19, a large portion of the resistor 5 and the armature 1, to the line conductor 4. A portion of the resistor 5 is thus short-circuited, causing an increase in the motor speed. When the current-limit relay 19, which is released upon

the closing of the contactor 10, closes in accordance with current conditions, a circuit will be established from the line conductor 3, through the coil 25, the overload relay 24, 5 the current-limit relay 19, the coil 15 and the push-button 9, to the line conductor 4. The contactor 11 will thereupon be closed to short-circuit an additional portion of the resistor 5. The armature circuit will now 10 extend from the contactor 7, which is connected to the line conductor 3 through the coil of the relay 18, the conductor 23, the contactor 10, the coil of the relay 19, the contactor 11, the coil of the relay 20, a portion 15 of the resistor 5 and the armature 1, to the line conductor 4. In similar fashion, the contactors 12 and 13 will close, upon their actuating coils 16 and 17 becoming energized, following the closing of the current-limit relays 20 and 21. The coils of the current-limit relays 18, 19, 20 and 21 will become de-energized with the closing of the contactor 13, the motor circuit extending 20 from the line conductor 3, through the coil 25, the contactors 7 and 13 and the armature 1 to the line conductor 4. The motor will 25 then operate at normal speed.

It will be noted that the push-button 9 is adapted to open all the control circuits. It 30 may, if desired, be placed at the point 6, in which event it would open the circuit of the coil 8 only. The push-button 9 may control any desired number of the control circuits.

When the voltage of the source falls to a 35 predetermined value, as, for example, 80% of normal voltage, the relay 26 opens to open the circuit of the coil 14, thereby to cause the opening of the contactor 10. The current-limit relay 19 will thereupon be automatically opened by its controlling spring 40 to cause the opening of the circuit of the coil 15, which, in turn, will cause the opening of the contactor 11. In similar manner, the coils 16 and 17 will become de-energized, 45 and, upon the opening of contactor 13, the resistor 5 is inserted in the motor circuit. The motor will thereupon continue to operate, but at slow speed.

If desired, the coils 14, 15, 16 and 17 may 50 all be placed under the direct control of the low-voltage relay 26, in which case, the contactors 10, 11, 12 and 13 would be opened together under low-voltage conditions.

Upon the voltage rising, say to 90%, the 55 coil 27 will effect the reclosing of the relay 26, which, in turn, will cause again the energization of the coil 14, whereupon the contactor 10 will become reclosed to effect again the short circuiting of a portion of the resistor 5. The relay 19, thereupon reclosing when the current drops to a predetermined 60 value, will cause the reclosing of the contactor 11, the operation of short-circuiting the resistor 5 being the same as that above 65 described.

The value of the voltage at which the relay 26 will operate may be changed by suitably adjusting, automatically or manually, the resistor 28.

When the current traversing the motor 70 circuit exceeds a predetermined value, the coil 25 will effect the opening of the overload relay 24 and this, in turn, will cause the de-energization of the coil 8 to cause the opening of the contactor 7. The motor will 75 thereupon be disconnected from the line conductors 3 and 4. Upon the reclosing of the overload relay 24, assuming that the push-button 9 remains closed, the circuit of the coil 8 will become reclosed to cause the reclosing of the contactor 7 and the reconnecting 80 of the motor to the line conductors 3 and 4. It will be noted that the relay 24 is latched in its open position until released manually. This arrangement prevents intermittent operation or "pumping" in case 85 of continuous overload.

The above-described operations take place automatically, in accordance with changes 90 in line voltage and the current traversing the motor circuit. It is not necessary that the control apparatus be readjusted after voltage failure. The push-button 9 may be located at some distant point and the operation of this button will effect the closing or 95 the opening of the motor circuits, as desired.

Many modifications will suggest themselves to those skilled in the art and I desire, therefore, that my invention be construed broadly except in so far as limitations may 100 be specifically imposed in the appended claims.

I claim as my invention:

1. The combination with an electric motor having a resistor associated therewith and a source of energy for said motor, of means comprising a low-voltage relay for inserting said resistor into circuit with said motor when the voltage of said source falls below a predetermined value, while the circuit of said motor is maintained, and for short-circuiting said resistor when the voltage of said source rises above a predetermined value.

2. The combination with an electric motor having an armature, a resistor in series therewith, a plurality of electromagnetic switches for short-circuiting said resistor and having actuating coils and a source of energy for said motor, of a relay operable at a predetermined minimum value of the voltage of said source for effecting the opening of the circuits of said coils, the circuit of said motor being uninterrupted.

3. The combination with an electric motor having an armature, a resistor in series therewith, a switch for short-circuiting said resistor and having an actuating coil and a source of energy for said motor, of a relay having an actuating coil connected to said source for controlling the circuit of said

resistor-switch coil and means whereby said controlling switch coil causes the closing of said controlling switch when the voltage of said source is above a predetermined value and causes the opening of said controlling switch when the voltage of said source is below a second predetermined value, and

means for maintaining the closure of the motor circuit while said controlling switch is open.

In testimony whereof, I have hereunto subscribed my name this 21st day of Jan., 1919.

ALBERT L. HARVEY.
